REINFORCEMENT STIRRUP ASSEMBLY

Frank R. McFarland, Kansas City, Mo., assignor
to Sheffield Steel Corporation, Kansas City,
Mo., a corporation of Ohio

Application August 26, 1939, Serial No. 292,093

4 Claims. (Cl. 72—61)

This invention relates to concrete beam reinforcements, particularly the stirrup elements thereof, and has for its principal object to provide a stirrup assembly wherein the stirrups are securely and accurately spaced in accordance with engineering practice, and adapted for collapse to flat condition to facilitate shipping and handling thereof.

Other objects of the invention are to provide a unit assembly of this character with form engaging portions to automatically center the assembly in the form; to provide selective stirrups with foot portions whereby they serve as chairs in supporting longitudinal reinforcement rods; to provide a unitary assembly which may be stocked in standard sizes and adjustable for use in beams of different widths as required by the designing engineer; and to provide an assembly wherein the chair elements space the stirrups above the bottom of the beam form.

In accomplishing these and other objects of the invention, as hereinafter pointed out, I have provided improved details of structure, the preferred form of which is illustrated in the accompanying drawings, wherein:

Fig. 1 is a perspective view of a beam form partly broken away and showing my improved unitary stirrup assembly in position therein.

Fig. 2 is a plan view of the stirrup assembly, part of which is shown in horizontal section.

Fig. 3 is a cross-section through the form showing the chair and spacing elements of the assembly for positioning the stirrups in the center thereof.

Fig. 4 is a similar section after the concrete has been poured in the form, and showing the stirrups imbedded therein.

Fig. 5 is a detail perspective view of the stirrup assembly shown in collapsed condition.

Fig. 6 is a plan view, partly in horizontal section, of the collapsed unit.

Fig. 7 is a detail perspective view of one of the stirrups forming the chair spacing elements.

Fig. 8 is a similar view of one of the intermediate stirrups.

Fig. 9 is a perspective view of a portion of one of the connecting wires.

Fig. 10 is an enlarged detail perspective view of one of the hinge connections between the stirrups and connecting wires.

Referring more in detail to the drawings:

1 designates my preferred form of stirrup assembly, and which includes a series of spaced stirrups 2, with the endmost and one or more of the

intermediate stirrups of modified construction to provide chairs 3, 4 and 5 adapted to spacingly support the longitudinal reinforcing rods 6 and 7 of a completed beam structure, as shown in Fig. 4. The stirrup elements constituting the chairs each includes spaced vertical rods 8 and 9 of sufficient length so that the lower ends 10 are adapted to seat on the bottom of the beam form 11, and the upper ends to extend into the upper portion of the beam and terminate in laterally extending arm-like ends 12 and 13, as clearly shown in Fig. 3. The rods 8 and 9 are connected by cross bars 14 which are spaced above the lower ends 10, and preferably welded thereto. The cross bars 14 have projecting ends 15 and 16 adapted to engage the side members 17 and 18 of a form, as shown in Fig. 1.

The ends 10 of the rods 8 and 9 thus form footing portions for spacing the longitudinal reinforcement rods 6 and 7 from the bottom 11 of the form, and the projecting ends 15 and 16 are adapted to center the stirrups within the form, as shown in Fig. 3.

The intermediate stirrups are preferably formed of rods bent to form horizontal bar portions 21, and upwardly extending bar portions 22 and 23 terminating in laterally, outwardly extending ends 24 and 25, corresponding to the laterally extending, arm-like ends 12 and 13 of the chair elements 3, 4 and 5. The vertical rod portions of the stirrups conform in spacing with the rods 8 and 9, and the rod portions thereof conform to the length of the rods from the cross bars 14 to the terminals 12 and 13, whereby all the terminals 21 and horizontal bar portions of the stirrups are adapted to align with the lateral terminals 12 and 13 and with the horizontal bars 14 respectively.

The vertical rod portions of the respective stirrups are provided at spaced points along the height thereof with crimps 26 and 27 to provide hinge portions offset from the axis of the rods. Connecting the crimp portions of the respective stirrups are pairs of wires 28 and 29, having loops 30 formed therein and substantially encircling the crimped portion of the rods to provide co-operating hinge portions whereby the respective stirrups are retained in hinged assembly. The portions of the rods on the respective sides of the offset seats formed by the crimps engage the upper and lower faces of the loop portions so that the spacing wires are retained in fixed spaced relation on the rod portions of the respective stirrups.

It is thus obvious that the unit is readily collapsed so that the stirrups are adapted to swing and the cross bar portions lie in substantially flat, overlapping relation as shown in 5 Figs. 5 and 6.

In using a collapsed stirrup assembly constructed as described, the vertical rod portions at one side are shifted with respect to the corresponding rod portions at the other side, until 10 the cross bar portions lie in spaced parallel planes extending transversely across the assembly as shown in Fig. 1. The unit is then mounted in the form so that the foot portions of the respective stirrup elements seat upon the bottom 15 board 11, and the ends 15 and 16 engage the side boards 17 and 18 of the form, as shown in Fig. 2. When thus applied the stirrup assembly is centered within the form, with the stirrups properly spaced since they are all retained by the connecting wires.

The longitudinal reinforcing rods are then inserted in the form so that they are supported on the horizontal bars 14 of the chair elements. When the reinforcement is in place and the concrete 25 poured as shown in Fig. 4, the stirrups, as well as the rods, are retained in their proper spaced relation with the faces of the beam and in their required position, since the spacing elements prevent shifting thereof incidental to 30 pouring of the concrete.

When a standard stirrup assembly is to be used in a form of narrower than standard width, the assembly may be partially collapsed so that 35 the ends of the horizontal bars 14 may be positioned therein.

With the construction above described, it is obvious that the stirrups may be accurately assembled in definitely spaced relation, and then 40 shipped and handled in collapsed condition, to the place of use, where the assembly is readily

erected and retained in its desired position in a form.

What I claim and desire to secure by Letters Patent is:

1. A reinforcement of the character described, including a plurality of stirrup members, and spacing members connecting the stirrup members, each of said connections including a crimp portion in one of the members interengaged with a loop portion in the member connected therewith to form hinge joints to positively retain said members in predetermined spaced relation. 10

2. A reinforcement of the character described, including a plurality of stirrup members, and spacing members connecting the stirrup members, each of said connections including a crimp portion in one of the members interengaged with a loop portion in the member connected therewith to form hinge joints to positively retain said members in predetermined spaced relation, 20 selected stirrup members having form engaging portions to center the reinforcement within a form.

3. A reinforcement of the character described, including a plurality of stirrups having crimp portions, and spacing wires having loop portions interengaging the crimp portions to hingedly connect and positively space the stirrups with respect to the wires. 25

4. A reinforcement of the character described, including a plurality of stirrups having crimp portions, and spacing wires having loop portions interengaging the crimp portions to hingedly connect and positively space the stirrups with respect to the wires, selected stirrups 35 comprising rods and cross bars welded to said rods at points between the crimp portions and the lower ends of said rods to provide foot portions for spacing the stirrups from the bottom of the form. 40
